METHOD FOR PRODUCING FABRICS
HAVING WEFT THREADSOtto Wahle, Prague, Czechoslovakia; vested in the
Alien Property CustodianApplication April 8, 1939, Serial No. 266,716
In Czechoslovakia February 24, 1939

1 Claim. (Cl. 66—1)

This invention relates to a method of producing hand knitted fabrics incorporating weft threads.

It has already been proposed to insert, during the manufacture of the knitted fabric, weft threads running unknitted through the said fabric. These known methods which can be carried out only by fitting additional weft thread guides to the already complicated knitting machines, makes it possible for the weft thread either to be inserted during the continuous knitting operation only in each second stitch of the fabric or to fix the thread between two neighboring rows. By unstitching one of these rows the weft thread becomes free also from the other of the two rows, so that the selvedge row always rests without weft thread.

According to another known method weft threads are inserted in each single stitch of all rows, but each of the weft threads is passed thereby transverse to the direction of the rows and through all of the rows of the fabric. In this method all rows of the fabric must be knitted simultaneously and this requires the mechanical employment of a plurality of knitting tools and of separate tools for drawing in the weft threads.

In the method according to the present invention, hand knitted fabrics may be produced wherein through each single stitch of each row a weft thread is passed concurrently with the formation of each stitch and consequently the knitted fabrics are given not merely the appearance but also to a certain extent the quality of woven fabrics and especially the fullness and inelasticity in the direction of the weft thread.

According to the invention the single hand stitches knitted in the usual manner are performed not only around the hand knitting tool but also around a weft thread, fixed longitudinally and detachably thereon, so that after completion of each row and withdrawing the tool from the completed row the weft thread remains threaded through all the stitches in that row. Subsequent rows of stitches may be produced in the same manner or without the simultaneous insertion of a weft thread. In the former case the weft thread may pass as a continuous thread through several rows of stitches or be previously cut to lengths each corresponding to the length of each row of stitches.

The knitting method according to the invention may be effected with knitting tools which differ from the hitherto used hand knitting tools only in that a weft thread can be firmly held thereon in the direction of their relative movement to the row of stitches, that is by means of fixing devices located near the ends of the tool.

In the accompanying drawing Figure 1 shows an example of the fabric knitted by the method

according to the invention with a weft thread fixed on it. Figure 2 illustrates by way of example a hand knitting needle adapted for the performance of this method. Figure 3 is a cross sectional view of the needle.

For producing the fabric a suitable length of weft thread 10 is attached to the knitting needle. For this purpose eyelets 3, 4 are provided adjacent to the points of the needle and interconnected by a longitudinal tapered groove 5 clamping the weft thread drawn through the eyelets and positioning the thread not to extend over the surface of the needle. By the aid of two such needles, the knitting needle according to the invention the knitting thread 11 is then knitted in the usual way into stitches and row of stitches. In this manner each stitch is knitted around the weft thread 10 fixed on the knitting needle. Now, in order to knit a row of stitches thus produced over on to a second needle, the two ends of the weft thread are released from the eyelets 3, 4 in the first needle, whereupon usual knitting is continued with the second needle into which another length of weft thread has been inserted if desired. As the needle is withdrawn from each row on completion, the stitches in said row have the weft thread 10 passing through them.

For the purpose of producing patterned knitted fabrics, some rows of stitches may be knitted with an inserted weft thread whilst in other rows of stitches the weft thread may be omitted, the appropriate needles being used for both kind of rows. Furthermore, if desired, the needles may be changed for others having a depth of groove such that several and, if desired, differently coloured weft threads may be inserted simultaneously.

Due to the insertion of the weft thread the knitted fabric grows more rapidly even when needles having the standard thickness are used, and the speed of growth may be still further increased by using heavier needles or by inserting heavier or multiple weft threads, without thereby reducing the tightness of the fabric.

What I claim and desire to secure by Letters Patent of the United States is:

A method of producing hand knitted fabrics with incorporated weft threads which consists in hand knitting the stitches by means of two co-operating hand knitting needles only, while having weft attachable longitudinally on the needles so that each single stitch is formed around the weft thread fixed on the needle and so that after completion of a row of stitches and after manually detaching the weft thread from the needle, the weft thread is embedded in each stitch of the completed row.

OTTO WAHLE.
